CARBURETOR

Reinhold von Becker, Darmstadt, Germany, and
Jesimir Djordjevitch, Paris, FranceApplication April 4, 1932, Serial No. 603,182
In Germany April 10, 1931

5 Claims. (Cl. 261—34)

Our invention relates to improvements in spray carburetors for internal combustion engines which have, besides the main spraying nozzle for the fuel and if necessary an idle running nozzle, also an auxiliary nozzle coordinated to the main nozzle and fed by a fuel supply pump actuated with the throttle element. In the old arrangements the control of the pump piston is effected positively with the adjustment of the 5 throttle valve by a lever fixed on the pivot axle of the throttle valve and connected at its free end with the piston or some kind of rigid lever connection between the piston and the rod system controlling the throttle valve.

10 According to this invention the positive coupling between the throttle element and the pump piston is replaced by a controlling element which is constructed or adjusted in such a manner that it only transmits the movement of the throttle valve to the pump piston in the case of certain predetermined positions of the throttle valve. This arrangement presents the advantage that an enriching of the mixture through the auxiliary nozzle only takes place whilst the throttle valve is in certain positions. By introducing a resilient element into the transmission element, for example a spring, the fuel is forced out of the cylinder in a uniform jet maintained for a long time; excessive pressures are taken up by the 20 spring and consequently damage to the pump is avoided. An adjustable spiral spring exchangeably fixed on the pivot axle of the throttle valve preferably serves as transmission element. The free end of this spring bears either directly or indirectly on the piston subjected to the action of a return spring and is of such dimensions that it is relieved when the throttle valve is in certain selected positions, that is, has no influence on the piston during the adjustment of the throttle valve 25 within a certain range. The commencement of the movement transmission can be determined by correspondingly dimensioning the return spring for the piston, and the stroke of the piston can also be limited by its thickness or by a pump being chosen having small dimensions in such a manner that from a certain position of the throttle valve which can be chosen the piston comes to a standstill whilst the throttle valve is further opened. The piston no longer follows the movements of the throttle valve so that, when the throttle valve is adjusted behind this predetermined point, no more fuel is supplied as is the case with a rigid coupling.

30 Several embodiments of the invention are illus-

trated by way of example in the accompanying drawing in which:—

Fig. 1 shows the carburetor partly in longitudinal section along line I—I in Fig. 2.

Fig. 2 is a top plan view of Fig. 1 partly in section.

Fig. 3 is a section along line III—III in Fig. 2.

Fig. 4 shows partly in longitudinal section a modification.

Fig. 5 shows on a larger scale the adjustable mounting of the spring on the axle of the throttling element, along the line V—V in Fig. 1.

The carburetor consists of a float chamber 1, a mixing chamber 3 with throttle valve 4 and main nozzle 5 which communicates by a conduit with the float chamber 1. A fuel pump 7 arranged between the float chamber 1 and mixing chamber 3 supplies the fuel flowing from the float chamber 1 through a conduit 8 during the working stroke of the piston 9 through a conduit 10 and auxiliary nozzle 11 into the mixing chamber 3. The air escapes from the pump cylinder 7 through a conduit 12 extending from the cylinder 7 into the open (Fig. 2). The piston 9 is held in its upper dead centre position by a spring 13. These parts do not form the subject matter of the present invention being described together with their operation in detail in our copending application Serial No. 603,181, filed April 4, 1932. The adjustment of the throttle valve 4 is effected in a well known manner by an adjusting lever 14. On the end of the pivotal axle 15 of the throttle valve 4 situated opposite the adjusting lever 14 an adjustable spiral spring 16 is exchangeably mounted, the free end of this spring bearing against the top of the piston 9 (Fig. 1). The spring 16 is secured to the axle 15 by a set screw 18 extending through a slot 19 at the end of the spring, thus enabling the latter to be adjusted, as shown in Fig. 5. When the throttle valve 4 is opened the spiral spring 16 is tensioned as the piston 9 is held back by the fuel enclosed in the cylinder. However, as soon as the tension of the spring 16 exceeds the counter pressure exerted by the return spring 13 and the fuel the piston 9 is pressed slowly into the pump cylinder 7 and supplies the fuel through the auxiliary nozzle 11 in a uniform jet which is maintained for a long time.

If the throttle valve 4 is returned to its closing position, the spring 16 is relieved, so that the piston 9 will be pushed by the return spring 13 into its initial position and the fuel supply of the pump will be interrupted during the adjustment of the throttle valve. According to the strength of the springs 16 and 13 the spiral spring 16 is lifted.

from the piston 9 when the throttle valve 4 is in its closing position, the stroke of the piston being limited by an abutment 20 (Fig. 4) and only commences to force the piston 9 into the cylinder 5 when the throttle valve 4 has reached a certain position or it remains bearing on the piston 9 (Fig. 1). In both instances the piston 9 is only shifted towards its lower dead centre position when the tension of the spring 16 exceeds the 10 pressure exerted by the return spring 13.

The device according to the invention may be arranged on all pump systems for carburetors and is not limited to the embodiments herein described or shown on the appended drawing.

15 We claim:—

1. In a spray carburetor controlled by a throttle valve having a pivotal axle, in combination with said throttle valve and its pivotal axle, a fuel feeding device, comprising a fuel pump, a 20 piston therein, and a spiral spring on said axle having a free end adapted to operate said piston with its free end.

2. In a spray carburetor controlled by a throttle valve having a pivotal axle, in combination with said throttle valve and its pivotal axle, a fuel feeding device, comprising a fuel pump, a piston therein, and an exchangeable spiral spring adjustably mounted on said axle having a free end and adapted to operate said piston with its free 30 end.

3. In a spray carburetor controlled by a throttle valve having a pivotal axle, in combination with said throttle valve and its pivotal axle, a 35

fuel feeding device, comprising a fuel pump, a piston therein, an exchangeable spiral spring adjustably mounted on said axle having a free end and adapted to operate said piston with its free end, and an abutment for limiting the upward stroke of said piston. 80

4. In a spray carburetor controlled by a throttle valve having a pivotal axle, in combination with said throttle valve and its pivotal axle, a fuel feed-device, comprising a fuel pump, a piston therein, a return spring adapted to act on said piston, an exchangeable spiral spring adjustably mounted on said axle having a free end and adapted to bear with its free end on said piston, the tensional strength of said spring when said throttle valve is in closing position being always less than the pressure exerted by said return spring. 85

5. In a spray carburetor controlled by a throttle valve having a pivotal axle, in combination with said throttle valve and its pivotal axle, a fuel feed device, comprising a fuel pump, a piston therein, a return spring adapted to act on said piston, an exchangeable spiral spring adjustably mounted on said axle having a free end and 100 adapted to operate said piston with its free end, and an abutment for limiting the upward movement of said piston, the tensional strength of said spiral spring when said throttle valve is in closing position being always less than the pressure exerted by said return spring. 105
